(57) **CLAIM**

The ornamental design for a windshield cover, as shown and described.

DESCRIPTION

FIG. 1 is a front elevational view of a windshield cover showing my new design;

FIG. 2 is a rear elevational view thereof;

FIG. 3 is a side view, taken from the left side of FIG. 1, the right side view being a mirror image thereof;

FIG. 4 is a top plan view thereof, the bottom plan view being a mirror image thereof;

FIG. 5 is a perspective view of my windshield cover in use; and,

FIG. 6 is a perspective view showing a single element of my design, namely the driver's side cover portion.

The broken lines showing a vehicle in FIG. 5 are for illustrative purposes only and form no part of my claimed design.
